UNITED STATES PATENT OFFICE.

FRANK J. HINDERLITER, OF TULSA, OKLAHOMA.

JOINT BREAKER.

Application filed October 5, 1923. Serial No. 666,708.

To all whom it may concern:

Be it known that I, FRANK J. HINDERLITER, a citizen of the United States, and a resident of the city of Tulsa, in the county of Tulsa and State of Oklahoma, have invented certain new and useful Improvements in a Joint Breaker; and I do hereby declare that the following is a full, clear, and exact description of the same, reference being had to the accompanying drawings, and to the numerals of reference marked thereon, which form a part of this specification.

This invention relates to a joint breaker, and is an improvement over the joint breaker shown in my pending application, Serial No. 536,067 filed Feb. 13, 1922. In the joint breaker disclosed in said pending application, the line of thrust or force was not always applied so as to be normal to the wrench handle, and it has been found that in some instances a part of the applied force was ineffective. The ineffective component of force sometimes tends to produce an outward or lateral strain upon the jack screw, and in cases of a very tight joint this ineffective lateral component of force would be lost. To overcome this objection, I have provided a jack screw in connection with a joint breaker, so that substantially all of the applied force will be delivered in a direction substantially normal to the wrench handle, whereby the liability of the rupture of parts is eliminated.

With these and other advantages in view, which will become more apparent in the following description and disclosures in the drawings, this invention comprises the novel mechanism and combinations hereinafter described and more particularly pointed out and defined in the appended claims.

In the accompanying drawings which illustrate a preferred embodiment of this invention and in which similar reference numerals refer to similar features in the different views;

Fig. 1 is a prespective view of my improved joint breaker illustrating its practical application.

Fig. 2 is a fragmentary top plan view of the joint breaker.

Fig. 3 is an enlarged front elevational view of the jack screw with the guiding track shown in section.

Fig. 4 is an enlarged sectional view through the power jack.

In referring to the drawings, there is illustrated a supporting platform 1 upon which an arcuate rack 2 is positioned. This rack is in the form of a T-rail having lower supporting flanges and an upper T-shaped head. The upper surface of the rack is provided with ratchet teeth, except for a short space at one end which is substantially smooth. An abutment or ratchet stop 3 is supported upon the toothed portion of the rack and may be adjusted thereon by means of a pawl and lever, as is well known in the art.

A jack shaft support 4 having a T-shaped groove in its bottom for receiving the T head of the rack, may be adjustably anchored upon the smooth portion of the rack by set screws or in any other manner. A hollow bearing 5 integral with or secured to the support 4 extends thereabove. The longitudinal axis of this bearing is offset at an angle to the base support 4 and the rack, as illustrated in Figure 4, for a purpose to be later explained. An internally threaded sleeve 6 is secured within the bearing 5 and a screw threaded jack shaft 7 is threaded in said bearing with its forward end projecting inwardly of the rack. The forward projecting end of this screw is provided with an apertured collar 8, upon which is rotatably mounted the jack screw head 9. This head is bifurcated in order to receive a wrench handle and between said bifurcation the said head is provided with a rounded V-shaped point 10 which lies in the longitudinal axis of the screw shaft and is adapted for engaging the part to be moved so that the thrust or force will be delivered in the axial line of the screw shaft.

In the drawing there is shown a drilling tool or rod 11 having a joint which it is desired to break. This tool extends through an aperture in the base 1 at substantially the center of the arcuate rack 2. A pair of wrenches 12 are secured upon the tool at an angle to each other, with one above and the

other below the joint in the tool. The handles of these wrenches extend over the arcuate rack. In operation, the stop 3 is adjusted upon the rack to bring one wrench handle into engagement therewith and the other into engagement with the bifurcated head of the screw shaft. Then by rotating the screw shaft through the lever 13 the said shaft is advanced, causing thereby rotation 5 of the wrench which is in engagement therewith for breaking the tool joint as is well known. After the joint is broken, the abutment 3 may be used to uncouple the parts. As the axis of the screw shaft is normal to 10 the wrench handle, all of the applied power will be effective in forcing the wrench as desired. It is evident that as the screw shaft 7 is rotated, the angles between it and the wrench will vary, since the screw moves in 15 a straight line while the wrench rotates in a circle. It is therefore impossible to always maintain the axis of the screw at exact right angles to the wrench handle. However, as 20 the length of movement of the screw shaft is very slight, the axis of the screw shaft will not deviate appreciably from the normal, and the parts are designed to force maximum 25 pressure against the wrench handle. According to this invention, the bearing 5 is so arranged or at such an angle with respect 30 to its base that the engaging point 10 on the head of the jack shaft 7 will engage the wrench at substantially right angles at the maximum load. When the screw shaft is in 35 its initial inward position it will be practically but not exactly at right angles to the wrench handle, the inner angle that it makes with the wrench will be slightly obtuse. However, as the screw shaft is rotated and 40 advanced, this obtuse angle will decrease so that the line of force will be at right angles substantially at the time that the maximum force is exerted to break the joint. During the initial rotation of the 45 jack screw, whatever slack exists is first taken up, then the resiliency or yield of the metal is taken up, so that the maximum breaking force will be exerted after the screw shaft has been slightly advanced, and 50 at this point it is contemplated that the screw shaft shall be substantially normal to the wrench it operates in order to avoid the intense lateral strains that might tend to rupture the jack screw support. The proper 55 application of the pressure as will be appreciated, is of great importance in view of the fact that in breaking large joints such as are now quite common, a great deal of power is necessary within a restricted space; as 60 much as thirty ton pressure on the wrench handles is sometimes required.

From the foregoing, it will be apparent that by arranging the jack screw so that it 65 will be substantially normal to the wrench handle at maximum load, substantially all

of the applied force will be effective for turning the wrench and no objectional lateral force will exist to rupture parts of the device. It should also be apparent that as the necessary force to rotate the jack shaft 70 becomes greater, the nearer the obtuse angle approaches a right angle. That is, as the force increases and rotates the wrench, the effective component of force increases.

I am aware that numerous details of construction may be varied through a wide range without departing from the principles of this invention; and I therefore do not purpose limiting the patent granted otherwise than necessitated by the prior art. 75

I claim as my invention:

1. In a joint breaker, an arcuate rack, an adjustable abutment thereon, a support upon said rack, a screw threaded bearing carried by said support and arranged at an angle thereto, a screw threaded jack shaft supported in said bearing and adapted for engaging substantially at right angles a wrench pivotally anchored at the center of the arc defined by said rack, when the applied force is substantially at a maximum. 80

2. In a joint breaker, an arcuate rack, an adjustable abutment thereon, a screw threaded bearing anchored upon said rack, the axis of said bearing being arranged at a horizontal angle to said rack, and a screw threaded jack shaft supported in said bearing and adapted for normally engaging at right angles a wrench pivotally anchored at the center of said rack at substantially the 85 time of maximum load. 90

3. In a joint breaker, an arcuate rack, an adjustable abutment thereon, a jack screw rotatably supported upon said rack and having its operative end extending inwardly of the rack for initially engaging a pivotally mounted wrench handle at an obtuse angle, and means for rotating and advancing said shaft whereby said obtuse angle is decreased to a right angle at maximum load. 100

4. In a joint breaker, an arcuate rack, an adjustable abutment thereon, a screw threaded jack shaft supported upon said rack in opposed relation to said abutment, said jack shaft being arranged at an angle to said rack and being provided with a rounded V-shaped end for the purpose set forth. 115

5. In a joint breaker, an arcuate rack, an adjustable abutment thereon, a housing adjustably anchored to said rack, a bearing in said housing having an axis extending at a transverse angle to said rack, and a jack screw threaded in said bearing. 120

6. In a joint breaker, an arcuate rack, an abutment secured upon said rack, a support upon said rack in opposed relation to said abutment, and a screw threaded jack shaft carried by said support, said jack shaft hav- 130

ing an axis obliquely intersecting said rack.

7. In a joint breaker, a base having an arcuate groove for receiving an arcuate member, a cylindrical housing carried by said base at a transverse angle to said base and a jack shaft threaded in said cylindrical member.

8. In a joint breaker, a base having an

arcuate groove, a cylindrical housing carried by said base, the axis of said housing intersecting said groove at an angle and a jack shaft threaded in said housing. 10

In testimony whereof I have hereunto subscribed my name.

FRANK J. HINDERLITER.
